UNITED STATES PATENT OFFICE.

JAMES M. DAYTON, OF TORRINGTON, CONNECTICUT, ASSIGNOR TO EXCELSIOR NEEDLE COMPANY, OF TORRINGTON, CONNECTICUT, A CORPORATION OF CONNECTICUT.

CARBURETER.

1,180,379.

Specification of Letters Patent.

Patented Apr. 25, 1916.

Application filed December 1, 1910. Serial No. 595,096.

To all whom it may concern:

Be it known that I, JAMES M. DAYTON, a citizen of the United States, residing at Torrington, in the county of Litchfield, 5 State of Connecticut, have invented certain new and useful Improvements in Carbureters, of which the following is a description, reference being had to the accompanying drawing, and to the letters and figures 10 of reference marked thereon.

The invention relates to new and useful improvements in carbureters, and more especially to carbureters which are provided with a main air inlet and an auxiliary air 15 inlet, which is normally held closed by means of a spring.

An object of the invention is to provide a carbureter of the above character with means independent of the mechanism for 20 holding the valve for the auxiliary air inlet closed, which means operates upon the valve to close the same while starting the engine.

In the drawings which show by way of illustration one embodiment of the invention; Figure 1 is a sectional view through a carbureter, showing my improvement applied thereto. Fig. 2 is a sectional view across the auxiliary air inlet showing the means for holding the valve for said inlet 25 closed. Fig. 3 is a detail in section, showing the locking device for the controlling lever. Fig. 4 is a detail showing in plan a spring mechanism for controlling the auxiliary valve.

The carbureter as shown in the drawings, consists of a main body portion 1 which is provided with a U-shaped passage 2 leading from the main air intake 3, to the auxiliary air inlet 4. A fuel nozzle 5 projects into the U-shaped passage 2 at the lower portion thereof, and is controlled by a suitable needle valve 6. The fuel mixed with the air is conveyed through the passage 7 to the engine. A suitable throttle 8 may be provided for controlling the supply of mixture to the engine. The auxiliary air inlet 4 is closed by a valve 9 mounted on a stem 10 which reciprocates in bearings 11 and 12. The outer end of the stem 11 is engaged by a suitable spring controlled mechanism which normally holds said auxiliary air inlet valve closed. As herein illustrated, said spring controlling mechanism consists of a rod 20, which bears against the 55 end of the stem 10 connected with the auxil-

iary valve 9. This rod 20 carries a spiral thread which meshes with a pinion 21. The pinion 21 is connected with the gear 22, and the gear 22 in turn meshes with a pinion on the arbor which is rotated by the spiral 60 spring 23. The spiral spring through the connecting gears operates to normally close the auxiliary valve 9. Said spring however, is so placed under proper tension as to allow the auxiliary air inlet valve to open under 65 the suction of the engine in the usual manner in this type of carbureter.

It is found in practice that when the auxiliary air inlet valve is under light 70 spring tension, which is the proper adjustment of the spring for controlling the valve when the engine is in normal action, that the suction of the motor will open the valve and the mixture will be too weak to start the motor by cranking. It is preferable to 75 have the mixture at the starting of the engine a little rich in order that the motor will start easily.

In order that the air inlet valve may be controlled during the cranking or starting 80 of the engine, I have provided a shaft 13 which is rotatably mounted in a suitable bearing in the casing of the carbureter, and said shaft at its upper end is provided with a laterally deflected portion forming an 85 arm 14, which when swung to the position shown in Fig. 1, bears against the inner face of the valve for the auxiliary air inlet and will force the same against the seat for the 90 valve and hold the same closed against the force of the suction stroke of the engine, tending to open the same. Said shaft at its lower end carries an arm 15 which may be connected by any suitable mechanism so as 95 to be conveniently controlled manually. The shaft 13 is free to move longitudinally in its bearings and a spring 16 bearing against the casing at one end, and against a shoulder 17 on the shaft at its other end, normally forces said shaft upwardly as 100 viewed in Fig. 1.

Mounted in a recess or pocket in the casing is a ball stud 18, also mounted in a recess formed in an extension to the arm 15 is a second ball stud 19. These two ball studs are so positioned as to coöperate with each other in holding the arm 15 either in a position so that the arm 14 rests against the valve 9, or in a position wherein said arm 14 is held entirely free of said valve. 110

The spring 16 will yield to allow the ball studs to slip one over the other.

In the operation of my device, when it is desired to start the engine, the lever 15 is 5 swung so as to bring the arm 14 into contact with the valve 9, which will close the valve and hold the same against its seat so that the suction stroke of the engine during the cranking will not open the valve. The 10 entire supply of air for the carbureter is drawn through the main air inlet and across the fuel nozzle which will increase the richness of the mixture and thus aid greatly in the starting of the engine. As soon as the 15 engine starts, the arm 15 may be manually swung in the opposite direction, and the valve 9 released so that it may operate in the normal manner.

While I have shown my improvement as 20 applied to the particular type of carbureter, it is obvious that said device may be used in connection with other forms of carbureters and it is also obvious that minor changes in

the details of construction of my device and the arrangements of parts may be made 25 without departing from the spirit of my invention as set forth in the appended claim.

Having thus particularly described my invention, what I claim as new and desire to secure by Letters Patent, is:—

A carbureter including in combination, a fuel nozzle, a main air inlet, an auxiliary air inlet, a valve for controlling said auxiliary air inlet, manually operated devices for holding said auxiliary air inlet valve closed 35 against movement under the suction stroke of the engine, and means for locking said manually operated devices with said valve in closed position.

In testimony whereof I affix my signature, 40 in presence of two witnesses.

JAMES M. DAYTON.
